FILAMENT FOR EVAPORATING REACTIVE METAL IN HIGH VACUUM APPARATUS

Lewis D. Hall, Palo Alto, Calif., assignor to Ultek Corporation, Palo Alto, Calif., a corporation of California

Filed Mar. 18, 1963, Ser. No. 265,709
6 Claims. (Cl. 219—275)

This invention relates to high and ultrahigh vacuum equipment and more particularly to apparatus for evaporating or subliming chemically reactive metal to form deposits which will trap or getter gas in a vacuum system.

In general, evaporator units include a filament and suitable holder assembly. The filament can include a reactive metal wire, such as titanium, closely wound around a refractory supporting core which is electrically heated to evaporate the titanium.

Ideally, in evaporator units for practical commercial high vacuum apparatus, the amount of metal evaporated for each watt of electrical power applied should be high to provide maximum efficiency. Total watts of input power should be low to minimize heating. As is known, the generation of heat in vacuum systems causes outgassing of components which tends to raise the pressure in the vacuum system. In dynamic, commercial equipment this problem has dictated the practice of employing elaborate cooling schemes, not uncommonly employing liquid nitrogen and the like. Where continuous pumping for extended periods in dynamic systems with high gas loads is desired, as much reactive metal as possible should be supplied without unduly increasing total watts of input power.

The foregoing objectives are, therefore, mutually incompatible and in commercial equipment represent severe restrictions. Thus, the total amount of reactive metal evaporated can be increased by enlarging the wire diameter of the reactive metal winding. However, the resultant increase in the power requirement tends to dictate installation of costly liquid cooling. If wire size is kept sufficiently small whereby a fan can provide simple air cooling, then the supply of reactive metal is inadequate for practical use.

Furthermore, in evaporator filaments of the kind described above, the reactive metal must be carefully heated to evaporation temperature without melting the metal. Using titanium, for example, once it begins to melt, the entire supply promptly melts and runs freely from the core.

It is a general object of the invention to provide an improved evaporator unit.

Another object of the invention is to provide an improved filament for evaporation or sublimation of reactive metal.

A more particular object of the invention is to provide an evaporator filament combining enhanced efficiency of evaporation, a power requirement low enough to employ air cooling, and a supply of reactive metal adequate for extended operation.

These and other objects of the invention will become more readily apparent from the following detailed description of a preferred embodiment when taken in conjunction with the accompanying drawing, in which:

FIGURE 1 shows, partly in section, a holder for supporting an evaporator filament;

FIGURE 1A shows in side elevation, a filament for use in the holder shown in FIGURE 1;

FIGURE 2 is an enlarged section view of FIGURE 1A in the region of line 2—2 thereof;

FIGURE 3 is an elevation section view further enlarged

2

of the detail defined by line 3—3 of FIGURE 2; and FIGURE 4 is similar to the detail of FIGURE 3 schematically showing the change therein after heating.

Generally, the filament for evaporation or sublimation includes a refractory support member adapted to be resistance heated. Axially spaced dams of refractory material encircling the support member are provided therealong. The interstices between the dams include a mass of reactive metal of a kind to be evaporated whereby the metal-filled interstices and dams generally define an encircling thickness, herein referred to as a "first layer." An overlying layer of reactive metal to be evaporated is then disposed to encircle the "first layer." The dams are undercut to permit the mass of reactive metal in the "first layer" to spread when softened by heating thereby providing enlargement of the heat transfer interface between the mass of reactive material and the support member. For example, the dams can be formed of a helically wound refractory wire. Refractory co-planar rings can also be distributed along the support member to form the dams. The completed filament is carried into the vacuum system by a holder assembly whereby spent filaments can be readily removed and replaced.

Referring to FIGURE 1A, a filament 10 is shown which is adapted to be supported between holders 21, 22 of refractory material, such as molybdenum, carried in a holder assembly designated generally by the reference numeral 20 as shown in FIGURE 1.

The above "first layer" of refractory dams and evaporative reactive metal is generally provided by a pair of closely wound, elongated wire or ribbon members wrapped around the refractory support member to form a first layer therealong. One of the ribbon members is comprised essentially of a refractory material and the other 35 a reactive metal. A second layer then is applied consisting essentially of reactive metal most conveniently in the form of a closely wound reactive metal wire or ribbon member.

It has been observed that with the foregoing filament arrangement, each encircling turn of the refractory ribbon member serves so that the reactive metal in the first layer can melt without running freely from the filament. At the same time, there is provided enhanced heat conductance via the interface with the support member since the annular refractory ribbon member permits the reactive metal, when softened by heat, to spread over an enlarged area of the support member due to its narrow circumferential line contact with the refractory ribbon member. In this manner, the transfer of heat from the support member is channeled primarily through the metallic mass between turns of the refractory winding. Further, the second layer tends to blend with the spreading material of the first layer to provide a highly heat conductive path throughout the reactive material being evaporated.

It has also been observed that this arrangement serves to minimize the power required to evaporate an overlying layer of reactive metal. The power required to evaporate the overlying layer is only very little more than that required to evaporate a single layer. The requisite power for evaporation of the filament is mostly utilized to maintain heat of evaporation in the outermost subsurface region of the reactive metal. In other words, the rate of heat loss is greatest near the exposed surface, whereas the heat loss distribution curve along a path extending radially through the rest of the reactive metal is otherwise fairly flat. The addition of the second layer, therefore, serves to permit the reactive material of the first layer to become hotter throughout its complete thickness and thereby increase efficiency of evaporation.

Referring to the drawings, filament 10 comprises a rod-like core member 11 of resistance heatable refractory

material. The material must be sufficiently rigid whereby when heated, it can properly carry the over-windings mentioned above. Suitable core material can be selected from the group consisting essentially of metals and alloys including rhenium, tungsten-rhenium, tungsten-molybdenum, or tungsten. The latter has been found to be particularly satisfactory.

The first layer 13 is formed by a bifilar close wound winding comprising a wire 14 of refractory material and another wire 15 of reactive metal material of a kind to be evaporated. The material of wire 14 can be selected from any suitable ductile, refractory material which lends itself to being close wound about member 11. Suitable refractory materials for this purpose include metals and alloys of the group consisting essentially of niobium, tantalum and molybdenum. The latter is particularly satisfactory. The refractory material for wire 14 must be such as to raise the melting point of the reactive metal of wire 15 when brought into contact with it. Furthermore, it must not form low melting eutectics with the reactive metal.

Suitable material for wire 15 must be capable of being bent around a small radius and, therefore, cannot be too stiff. Suitable reactive material, therefore, may be selected from the group consisting essentially of vanadium, yttrium, or titanium, or alloys thereof. Titanium has been found to give particularly good results.

In order to provide layer 13 with a substantially uniform thickness, the diameter of wires 14, 15 preferably should be substantially the same. While these diameters can vary between limits depending upon the power requirement of the unit, a particularly desirable range of diameters has been found to lie between on the order of 0.015 and 0.045 inch using either molybdenum or niobium.

An overlying layer 16 of reactive metal to be evaporated is preferably formed by a close wound wire 17 of suitably ductile chemically reactive metal preferably selected from the group consisting essentially of vanadium, yttrium, titanium or alloys thereof. Particularly advantageous results have been obtained using titanium. An adequate commercially practicable supply of reactive metal commensurate with a low power requirement is obtained using a wire diameter on the order of between 0.015 inch to 0.045 inch.

Example 1

A particularly advantageous example of filament 10 has been formed by employing a tungsten core member 11 of 0.022 inch diameter and a molybdenum wire 14 having a diameter of 0.015 inch and a titanium wire 15 of substantially like diameter. Wire 17 of layer 16 is formed with a diameter of 0.015 inch of titanium.

Another example of a suitable filament can include a tungsten core 11 having a diameter of 0.065 inch, a molybdenum wire 14 and titanium wire 15 having a diameter of 0.045 inch and an overwinding wire 17 of titanium having a diameter of 0.045 inch.

Yet another example includes a tungsten core 11 having a diameter of 0.020 inch, a molybdenum wire 14 and titanium wire 15 each having a diameter of 0.010 inch and an overwinding wire 17 of titanium having a diameter of 0.020 inch.

Holder assembly 20 supports filament 10 whereby it can be heated to evaporate the metal of wires 17 and 15.

Means for disposing filament 10 in a vacuum system include a base assembly 23. Assembly 23 includes a flanged cylindrical base member 24. Member 24 carries a plurality of studs 25 attached thereto by screws. A cylindrical sleeve 26 is supported by base member 24 and closed at its open end by a top cap member 27. Cap member 27 is retained against the end of member 26 by screws carried in the ends of studs 25.

Means for supporting filament 10 in a heating circuit include a sintered metallic oxide terminal 28 such as sold by the U.S. Stoneware Co., Tallmadge, Ohio, under the

mark "Alite." Terminal 28 extends through member 24 and connects with an electrode 29. A braided cable 30 and cap connector 31 form a lead-in to electrode 29. Cable 30 is disposed to be energized by connections made with a terminal supported by the insulating bushing 32. A refractory insert 22, for example, of molybdenum, is carried in the end of electrode 29 and adapted to receive one end of filament 10.

Base member 24 supports a second electrode 33. Means whereby mutual support is provided between electrodes 29 and 33 includes an annular ceramic bead 34 carried by electrode 29. A support plate 35 is retained on bead 34 by washers 36. Electrode 33 extends through an opening in plate 35. The free end of electrode 33 carries a filament-retaining member 37 formed with an opening 38. Opening 38 extends through member 37 and is aligned with holder 22. Opening 38 similarly carries a refractory holder 21, adapted to receive one end of filament 10. A retaining collar 39, together with a high vacuum O-ring seal 40 encircles the flange of base member 24 whereby the entire unit can be screwed into place and retained by a coating fitting of the vacuum system (not shown).

Thus, filament 10 is disposed to be connected into an electrical circuit whereby it can be heated to evaporate the reactive metal thereon.

In operation it has been observed that the reactive metal of wire 15 will soften and tend to spread beneath the turns of refractory wire 14 as in the region 41. This spreading has been observed to provide enhanced heat conductance between core member 11 and wire 15 by enlarging the interface therebetween. As wire 15 is heated and softens, heat transfer therethrough serves to soften the turns of wire 17 as shown in FIGURE 4 tending to provide a merged mass of reactive metal free of heat retarding interfaces. As noted above, it has been observed that the temperature distribution through wire 15, for example between points "a" and "b" on the axis 42 will have only a slight slope, whereas the greatest heat loss can be expected to be found near the exposed surface of layer 16, for example, say between points "c" and "d." On the other hand, heat transfer through the refractory wire 14 is impeded substantially by the circumferential line contact at "e." The turns of wire 14 form dams to prevent the heated mass of wire 15 therebetween from running freely from core 11.

From the foregoing it will be evident that considerably more titanium can be evaporated with a very small percentage increase in power. For example, using the structure described in Example 1 above, the power requirement to evaporate the titanium therein can be on the order of 250 watts. However, on the of 240 watts are required if layer 16 is not employed. Accordingly, virtually three times more titanium can be evaporated with only a 4% increase in power.

I claim:

1. A filament for evaporating reactive metal in a vacuum system to trap gases therein, comprising a support member of resistance heatable refractory material, means forming axially spaced dams of refractory material along said core member, a mass of reactive metal of a kind to be evaporated disposed around said member between said dams to define a first layer therewith, and a layer composed only of reactive metal to be evaporated extending along said support member overlying said first layer and in heat conducting physical contact with at least the reactive metal of said first layer.

2. A filament as defined in claim 1 wherein the dams are undercut to permit said mass of reactive metal to spread thereunder, upon softening, to provide enlargement of the heat transfer interface between said mass of reactive metal and said support member.

3. A filament as defined in claim 1 wherein the dams are formed by spaced turns of wire closely encircling said support member.

4. A filament for evaporating reactive metal in a vacuum system to trap gases therein comprising a support member of resistance heatable refractory material, a pair of elongated ribbon members closely wound around said member to form a first layer thereon, one of said ribbon members being comprised essentially of a refractory material and the other of a reactive metal, and a second layer disposed contiguously around said first layer and consisting essentially of only reactive metal to be evaporated, said second layer being in heat conducting physical contact with at least the reactive metal of said first layer.

5. A filament as defined in claim 4 wherein the refractory material of said first ribbon member consists essentially of metals or alloys selected from the group consisting of molybdenum, niobium and tantalum.

6. A filament for evaporating reactive metal in a vacuum system to trap gases therein comprising a stiff tungsten core member, a pair of wire-like ribbon members closely wound around said member to form a first layer thereon, one of said ribbon members being comprised essentially

5

of molybdenum and the other ribbon member of titanium, and a second layer contiguous to said first layer and consisting essentially of only titanium, said second layer being in heat conducting physical contact with at least the reactive metal of said first layer.
